[57] CLAIM

The ornamental design for a portfolio, substantially as shown and described.

DESCRIPTION

FIG. 1 is a perspective view of a portfolio showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a left side elevational view of the portfolio shown in FIG. 9, but with the closure flap in a closed condition; and

FIG. 9 is a front perspective view similar to FIG. 1, but showing the portfolio in an expanded condition, and with its closure flap in an open position.

FIG. 1

FIG. 2

FIG. 3

FIG. 4

FIG. 5

FIG. 5

FIG. 6

FIG. 7

FIG. 9
